US0D1097216S

(12) **United States Design Patent** (10) **Patent No.:** **US D1,097,216 S**
Voss et al. (45) **Date of Patent:** **** Oct. 7, 2025**

(54) **FREE-STANDING BALLASTED GUARDRAIL SUPPORT FOOT**

(71) Applicant: **SAYFA R&D PTY LTD**, Boronia (AU)

(72) Inventors: **Murray Voss**, Boronia (AU); **Barry Voss**, Boronia (AU)

(73) Assignee: **SAYFA R&D PTY LTD**, Boronia (AU)

(***) Term: **15 Years**

(21) Appl. No.: **29/929,721**

(22) Filed: **Feb. 23, 2024**

(30) **Foreign Application Priority Data**

Dec. 13, 2023 (AU) 202318383

(57) **CLAIM**

The ornamental design for a free-standing ballasted guardrail support foot as shown and described.

DESCRIPTION

FIG. 1 is a top perspective view of a free-standing ballasted guardrail support foot, showing our new design;

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

1 Claim, 8 Drawing Sheets
